UNITED STATES PATENT OFFICE

126,722

DESIGN FOR A LINE INSULATOR

Lorell John Schilling, Brookfield, Ill., assignor to
Babson Bros. Co., a corporation of Illinois

Application August 2, 1940, Serial No. 94,135

Term of patent 14 years

To all whom it may concern:

Be it known that I, Lorell John Schilling, a citizen of the United States, residing at Brookfield, in the county of Cook and State of Illinois, have invented a new, original, and ornamental Design for a Line Insulator, of which the following is a specification, reference being had to the accompanying drawing, forming a part thereof, in which:

Figure 1 is an end elevational view of the insulator; Figure 2 is a side elevational view of the insulator in its position of normal use; and Figure 3 is an elevational view of the other end of the insulator.

I claim:

The ornamental design for a line insulator, as shown.

LORELL JOHN SCHILLING.
